UNITED STATES PATENT OFFICE.

ROBERT KIESERLING, OF ALTONA, GERMANY.

CEMENT PAVING.

No. 839,600.

Specification of Letters Patent.

Patented Dec. 25, 1906.

Application filed June 2, 1905. Serial No. 263,398.

To all whom it may concern:

Be it known that I, ROBERT KIESERLING, a subject of the German Emperor, and a resident of Altona, Elbe, Germany, have invented a new and Improved Cement Paving, of which the following is a full, clear, and exact description.

The present invention relates to improvements in the production of cement paving for streets, roads, floors, yards, closed rooms, and so on.

One part of the subject-matter of my invention relates to the production of elastic joints in cement paving, which joints make the same permanently free from cracks.

Another part of the subject-matter of my invention relates to means for producing such elastic joints in the paving.

As is well known, irregularly-running cracks appear after a short time in paving made from concrete or other cement mixtures, which cracks lead to the destruction of the pavement. According to my invention I avoid this irregular formation of cracks by providing for the occurrence of cracks at definite places and by arranging for them to run in a direction previously determined upon.

With this object in view I embed in my new paving, made from cement or any preferred cement mixture, but preferably from fine-grained concrete, an iron armature fastened to the paving surrounding it suitably by means of hooks, gagers, or in any suitable manner, said armature being in the form of a channel. I fill these channels with an elastic substance preventing the penetration of water—for example, tar, hard-lead lute, or caoutchouc. I produce the above-mentioned channel by embedding in the paving two iron bars parallel to one another and arranged at a distance of about one centimeter from one another. Said iron bars may consist of an undivided strip or of several strips ranged in a row. These bars or strips are connected firmly with the adjacent paving. I connect the bars or strips firmly with the surrounding paving in any suitable manner, so that a gap can never arise between the two. The form, breadth, and position of the channels produced in the paving in this way can vary to a very large extent. I prefer in general to lay such channels transversely through the paving. However, the same may be made rectilinear or curved or even

serpentiform. I also employ angular channels, and, in fact, I do not limit myself at all to any definite form, size, or position for such channels. After the paving has set I fill the channel with tar, pitch, or any other substance which is as impermeable as possible to water. In addition to these transverse channels I lay similar channels at the sides of the paving in such a way that the same form the bounding-lines of the paving or lie near the side edges of the paving.

In order to illustrate my present invention more clearly, I will now refer to the accompanying drawings.

In said drawings, Figure 1 is a plan of a part of a street provided with my new paving. Fig. 2 is a vertical section, on a larger scale, through an elastic joint according to my invention produced in a street-paving. Fig. 3 is a side elevation, shown partly broken, of the iron armature which is employed according to my invention for the production of a channel. Fig. 4 is a section on the line 5 5 in Fig. 5. Fig. 5 is a plan, shown partially broken, of the iron armature represented in Fig. 3. Fig. 6 is a plan of a part of this armature. Fig. 7 is a section on the line 6 6 in Fig. 6. Fig. 8 is a side elevation, drawn on a larger scale, of a hook adapted to serve for connecting the sides of the channel with the paving.

The same reference characters indicate in all the figures the same or similar parts.

The street represented in Fig. 1 consists, essentially, of street-paving *a* and lateral curbstones *b b'*, which can be manufactured from natural or artificial stone.

The street-paving *a* is traversed by channels *c c'* and channels *d d'*. The channels *c* are contiguous with the curbstones *b* and the channels *c'* with the curbstones *b'*. It must, however, not be forgotten to emphasize the fact that the channels *c c'* could also lie at some distance from the curbstone. In this case also they may suitably run parallel to the curbstones.

The channels *d* and *d'*, in place of which, of course, channels of other form and running in another direction could be employed, run obtusely together and form an angular channel *d²*, which extends from the channels *c* to the channels *c'*. As is evident from Fig. 1, not only one channel *d d'*, but several such channels, at equal or unequal distances from one another, are embedded in the paving. I

prefer to make the distance between these channels about fifteen to twenty feet; but I do not, of course, limit myself to observing this distance.

5 The upper edges of the channels $c' c' d' d'$ lie exactly in the plane of the street-paving a . The latter may sometimes consist of an undivided layer of concrete. However, I usually prefer to produce this paving from a plurality of, usually two, layers a' and a^2 , lying one above the other, of which the latter is made from specially hard concrete having the capacity of offering great resistance. In the layer a^2 the above-mentioned channels 10 are produced. This is effected in the following way: After the under layer a' has set, which layer, moreover, I wish especially to point out, might also consist of separate concrete slabs, an area a^3 is covered with a suitable concrete, which is advantageously rammed down, this concrete extending, indeed, to the sides of the previously-laid channels $c' c'$ and $d' d'$. Each channel consists of iron rails (pieces of flat iron) $e' e'$, on the outer 15 side of which, and consequently on the side turned toward the concrete layer a^2 , lugs e^2 are situated, said lugs being provided with eyes through which hooks f can be placed. These hooks are embedded in with the concrete layer a^2 and cause the rails e to firmly 20 adhere to the concrete after the hardening of the layer. It is obvious that instead of such hooks any other desired means may be employed in order to connect the rails $e' e'$ firmly 25 with the concrete surrounding them. The rails e' are parallel to the rails e and may be at a distance from one another of about one centimeter. In order to obtain this distance in a simple and certain manner, round iron 30 rods g or similar rod-shaped pieces are placed vertically between the rails e and e' and clamps h are then slipped over the latter, said clamps being taken off subsequently—that is, after the rails have been surrounded 35 with concrete and after the latter has sufficiently set to permit it being trodden upon. The removal can be readily effected by withdrawing the clamps upward. After the area a^3 has been finished a new area a^3 is formed 40 from the concrete, the latter being spread out and rammed, starting from the rails e or e' . In this manner one field a^3 after another is produced, the channels $c' c'$ being formed in exactly the same manner near the curbstone 45 $b' b'$ as the channels $d' d'$. After the concrete of the upper layer has sufficiently set the rods g are withdrawn from the empty space i and the latter is filled up with tar i' or the like. I sometimes prefer to employ supporting- 50 plates k for the rails $e' e'$, said plates k being placed upon the layer a' at short distances of about two to three feet from one another, the rails $e' e'$ being then placed upon these. As can be seen from Fig. 2, a cap k' is placed 55 over each end of these plates k . The sides k^2

of each cap k' do not touch the supporting- 70 plate k , but a space k^3 is left free between the cap and the plate. The object of the formation of this space k^3 is to prevent the concrete layer a^2 advancing against the supporting- 75 plates k and displacing the same on account of the contraction occurring in consequence of variations in temperature. By arranging the caps k' in the manner represented a displacement of the plate k is completely out of 75 the question.

Having thus described my invention, what I claim as new, and desire to secure by Letters Patent, is—

1. A concrete or cement pavement, comprising two superposed layers, and two flat iron bars set on edge, adjacent to each other, upon the lower layer and embedded in the upper layer, which registers with the top edge of the bars, and an elastic substance 85 filling the channel between the bars, substantially as described.

2. A concrete or cement pavement, comprising two superposed layers, and two adjacent, continuous rows of flat iron bars set 90 on edge, end to end, upon the lower layer and embedded in the upper layer, and an elastic substance filling the channel between the bars, substantially as described.

3. A concrete or cement pavement, comprising two superposed layers, and two adjacent rows of flat iron bars set on edge upon the lower layer and embedded in the upper layer, an elastic substance filling the channel 100 between the bars, said bars presenting perforated bosses at intervals, and hooks passing through the bossed parts and lying embedded in the upper layer, substantially as described.

4. A concrete or cement pavement, comprising two superposed layers, plates located at intervals upon the lower layer, two adjacent rows of flat iron bars set on edge upon the said plates and embedded in the upper layer, and an elastic substance filling the 105 channel between the bars, substantially as described.

5. A concrete or cement pavement, comprising two superposed layers, plates located at intervals upon the lower layer, caps partly 115 overlapping the plates, two adjacent rows of flat iron bars set on edge upon the said plates and embedded in the upper layer, and an elastic substance filling the channel between the bars, substantially as described.

6. A concrete or cement pavement, comprising two superposed layers, plates located at intervals upon the lower layer, caps partly overlapping the plates and preserving a space 125 between their edges and the paving material, two adjacent rows of flat iron bars set on edge upon the said plates and embedded in the upper layer, and an elastic substance filling the channel between the bars, substantially as described.

7. A concrete or cement pavement, comprising two superposed layers, and two continuous rows of flat iron bars set on edge, end to end, upon the lower layer and embedded in the upper layer, an elastic substance filling the channel between the bars, the butt-joints of the bars of the one row being displaced relatively to the butt-joints of the adjacent row, substantially as described.
- 10 8. A concrete or cement pavement, comprising two superposed layers, and a plurality of pairs of rows of flat iron bars set on edge upon the lower layer and embedded in the upper layer, an elastic substance filling the channel between the bars, and each pair of rows being located in any desired position relatively to the other pairs of rows, substantially as described.
- 15 9. A concrete or cement pavement, comprising two superposed layers, and a plurality of pairs of rows of flat iron bars set on edge upon the lower layer and embedded in the upper layer, an elastic substance filling the channel between the bars, and there being one pair of rows located at each side of the pavement and cross pairs of rows con-
- necting the lateral rows, substantially as described.
- 10 10. A concrete or cement pavement, comprising two superposed layers, and a plural- 30 ity of pairs of rows of flat iron bars set on edge upon the lower layer and embedded in the upper layer, an elastic substance filling the channel between the bars, and there being one pair of rows located at each side of the 35 pavement and cross pairs of rows, presenting an obtuse angle, connecting the lateral rows, substantially as described.
11. A concrete or cement pavement, comprising two superposed layers, and two ad- 40 jacent rows of flat iron bars set on edge upon the lower layer and embedded in the upper layer, and an elastic substance filling the channel between the bars, substantially as described.

In witness whereof I have hereunto signed my name, this 17th day of May, 1905, in the presence of two subscribing witnesses.

ROBERT KIESERLING.
